UNITED STATES PATENT OFFICE.

ERNEST MEYERS, OF NORFOLK, VIRGINIA, ASSIGNOR OF ONE-HALF TO
JACOB A. ROSENFIELD, OF CHICAGO, ILLINOIS.

SAFE.

SPECIFICATION forming part of Letters Patent No. 508,895, dated November 14, 1893.

Application filed April 27, 1893. Serial No. 472,062. (No model.)

To all whom it may concern:

Be it known that I, ERNEST MEYERS, of Norfolk, in the county of Norfolk and State of Virginia, have invented certain new and useful Improvements in Safe-Boxes; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

This invention relates to certain improvements in safe or strong boxes, or the like.

The object of the invention is to provide an improved strong or safe box exceedingly cheap, simple and durable in construction, and so formed and constructed as to be burglar proof, and not capable of picking or opening with seeming intent, and which is conveniently portable and can be employed by business men to carry money or valuable papers to and fro, or can be employed at home to receive valuable papers.

A further object of the invention is to provide an improved strong box which can be detachably locked in an improved manner to a suitable base, in such a manner that the box can be unlocked from the base without unlocking the cover of the box and which is so constructed as to conceal the base when locked thereon, so that the edges of the box will rest on the table or other support completely concealing the base and securely locking the box in position.

A further object of the invention is to provide a portable box with a false bottom having an improved secret lock for securing the same, whereby a secret compartment is formed with said box beneath the false bottom.

A further object of the invention is to provide an improved strong box having an improved form of lock arranged to lock the box to a base and also lock the cover of the box so that the box can be unlocked from the base without opening or unlocking the cover.

The invention consists in certain novel features of construction and in combinations of parts more fully described hereinafter and particularly pointed out in the claims.

Referring to the accompanying drawings:— Figure 1 shows the box in perspective with the lid swung up and open, and also showing the false bottom open. Fig. 2 is a cross sectional view of the box, the parts being shown closed and locked and the box being shown locked to the improved base. Fig. 3 is a cross sectional view taken through the lines $x-x$, Fig. 2, showing the locks in locked position, locking the lid and the false bottom, and the box to the base. Fig. 4 is a similar view showing the lock in unlocked position to permit release of the box from the base and to permit raising of the cover, the key being shown in dotted lines. Fig. 5 is a detail view of a portion of the main sliding lock. Fig. 6 shows in plan the various tumblers of the lock separated. Fig. 7 is a cross sectional view through the tumblers of the lock showing them in their normal locking positions. Fig. 8 is a corresponding cross sectional view showing the key raising the tumblers, and in the act of unlocking the box.

In the drawings, the reference letter *a*, indicates a metallic box strongly constructed of suitable material such as sheet steel or the like, and provided with the cover or lid *b*, preferably arranged to swing upwardly, being hinged at one edge to the top of the box. However I do not wish to limit myself to hinging the lid to the box. A narrow vertical space or compartment extends across the flat end of the box, and contains the various locking mechanism. The lid is provided with one or more keepers *c*, preferably notched as shown which turn down through openings in the top of said space or compartment when the lid is lowered and are engaged therein by the locking bolt hereinafter to be described.

d, indicates a false bottom located a suitable distance above the main bottom of the box, and preferably composed of a sheet or plate of metal at one end hinged on suitable pivots extending into the side of the box so as not to be noticeable from the top of the false bottom when it is in its normal lowered position, so that the false bottom swings vertically as shown. A suitable coiled spring *e*, is preferably secured to the side of the main box at a point beneath the false bottom so as to exert a constant tendency to throw said

bottom up and open. The free end of said false bottom on its under side is provided with a suitable downward projecting keeper *f*, preferably notched as shown which is normally engaged by a suitable lock, hereinafter to be described which holds the false bottom down in its normal locked position, although I do not wish to limit myself to any peculiar kind of a spring for throwing the false bottom open, but have described a coiled spring as shown as preferable. The main bottom *g*, of the box is slightly elevated as shown so that the side edges thereof project down beneath the plane thereof. The said main bottom is provided with openings extending into the space containing the locking mechanism. The rear side of the box at its lower end is turned inwardly as shown to form the inwardly extending horizontal edge, flange or ledge *i'*, clearly illustrated in Fig. 2.

h, indicates a metallic base strongly and firmly secured by suitable means to a table, counter or any other place where it is desired to locate the strong box so that it cannot be moved except by the person having the proper key. This base is preferably composed of a sheet of metal of a size to fit within the depending edges of the sides of the strong box, that is the base is approximately of the same dimensions as the bottom of the box. This base near its front end is provided with the upwardly projecting notched keepers *i*, adapted to extend up through the openings in the bottom of the box into the space in the box containing the lock. The rear edge of the base is slightly raised so as to extend above the said ledge or horizontal inwardly extending flange formed by the depending side edge of the rear side of the box. It will thus be seen that in placing the box on the base, the box is tilted, that is, its front is slightly raised while said flange is being slipped under the rear elevated edge of the base. When this is done the front end of the box is dropped, and the keepers of the base enter the lock. The lock can then be operated to lock the box on the base. When the box is on the base, the base is completely concealed by the depending edges of the sides of the box so that to all appearances the box is resting on the table corner or other place. This is a point of advantage in several respects.

3, indicates the double sliding locking bolt confined in the said compartment in the front end of the box to lock the cover on the box and to lock the box to the base so that they can be independently released. The bolt consists of a horizontal plate *3*, at its ends having the vertical arms *4*, extending up and down as shown and at their lower ends having the horizontally extending locking ends *5* extending in the same direction and adapted to enter the notches of the keeper of the base plate to lock the box on the base plate. The upper ends of said arms *4*, are provided with the laterally extending locking ends *6*, pro-

jecting in the same direction as the locking ends *5*, and arranged to enter the notches in the keepers of the lid and lock the lid. These locking ends *5* and *6* are so relatively arranged or constructed that when the locking bolt is moved laterally the ends *5* will release the keepers of the base before the ends *6* have released the keepers of the lid. In the present instance this is accomplished by having the locking ends *5* shorter than the locking ends *6* so that when the bolt is moved to the right the base keepers will be released before the lid keepers have been released. The upper edges of the locking ends *6* are preferably beveled as shown so that the lid can be automatically locked by pressing it down and throwing the bolt laterally so that it will spring back in a locking position when the keepers of the lid are forced completely in their normal positions when locked.

8, indicates the key hole in the front side of the box, and *7* indicates the pin to receive the key. This pin is located beneath the series of tumblers *9*, *10*, *11*, and *12*, at corresponding ends pivotally mounted on a pin *13* secured to the rigid partition closing off the lock compartment and passing through a slot in the bolt. The free end of the tumblers are yieldingly held down by springs as usual. These tumblers are provided with registering openings or slots *14*, in which the lateral pin *15* rigid with the bolt slides and projects. These tumblers and slots therein are so arranged that when the bolt is in locked position locking both the lid and the box to the base, the said pin *15*, is located at the outer end of said slot in the tumbler behind the depending lugs *16* projecting down from the upper end edges of the said slot *14*, so that the tumblers hold the locks rigidly in locked position to prevent release thereof until the tumblers are raised to exactly the proper position by the tongue of the key, and then as the key is turned the tongue will enter the notch *17*, in the lower edge of the lock and will throw the lock the desired distance. The pin *15* then passes beneath the lug *16* and above the lug *19* beneath the same into the slot at the inner sides of said lugs. This operation which is accomplished by a single turn of the key will throw the lock to the right a distance that will release the locking ends *5* from the base keepers but will not release the ends *6* from the lid keepers. When the locking bolt is in this position it is yieldingly held by the spring *20* forcing the pin *15* against the inner sides or edges of the lugs or stops *16* of the tumblers. When the locking bolt is in this position to unlock the lid it is only necessary to insert the key and turn it about one half way around thereby moving the bolt the distance between the stops *16* and the inner ends of the openings in the tumblers which is sufficient to release the locking ends *6*, from the lid keepers and permit the lid to be raised while the locking bolt is held by the key. See Fig. 4. When

the key is released or turned completely around the spring 20 forces the bolt back to locking position respecting the lid but not the base. When the bolt is in the position shown in Fig. 3 and it is desired to unlock the lid the key must be turned completely around once and then half way around and held as just mentioned.

When the parts are in the position shown in Fig. 4 and it is desired to lock the box to the base the box must be placed on the base as before described and then the key inserted and turned to the left and the tumblers will be raised to the proper point so that when the tongue of the key engages the notch 21 of the bolt and moves the bolt to the left the lug 15 will be carried between the stops 16, 19 of the tumblers to the front ends of the openings in the tumblers thereby moving the locking ends 5, 5, of the lock into the notches of the keepers of the base L'. By reason of the employment of the peculiar tumblers the lock can be opened only by the particularly constructed key adapted therefor.

A suitable secret lock is provided for the false bottom in the present instance consisting of the sliding bar 22, located behind the vertical partition forming the lock chamber and provided with a lateral beveled locking lug 27 projecting through an elongated slot in said partition so that the spring 26 will yieldingly hold the said bar with its locking lug beneath or in the path of the keeper of the false bottom, the said locking lug being beneath the false bottom when closed and located in the notch of the keeper thereof thereby holding the bottom down until the bar is moved laterally to release said lug from the keeper when the spring of the false bottom will throw the false bottom up. When the false bottom is pressed down the locking lug will by reason of its beveled edge and the spring 26 automatically lock the said bottom. A vertical lever 23 fulcrumed between its ends at 24 and at its lower end pivoted to the outer end of said bar and having the notch 25 in its upper end near one of the openings through the lock containing chamber, moves said bar longitudinally to unlock the false bottom. The said lever can be swung to move said bar by a straight instrument or piece of metal inserted through said opening for the lid keeper and entering said notch. Of course this mode of opening the false bottom is supposed to be a secret with the owner of the box.

It is evident that various changes might be made in the forms, constructions and arrangements of the parts described without departing from the spirit and scope of my invention. Hence I do not wish to limit myself to the constructions herein set forth but consider myself entitled to all such constructions as fall within the spirit and scope of my invention.

Having thus fully described my invention, what I claim as new, and desire to secure by Letters Patent of the United States, is—

1. The flat rigidly secured base having keepers extending out therefrom and having one end elevated substantially horizontally, 70 in combination with a box having the depending sides arranged to extend down at the edges of said base so as to completely surround and conceal the base, the depending edge of one side of the box being turned in 75 to form a hook to fit beneath said raised end of elevated edge of the base as set forth, the box having openings in its bottom to receive the keepers, and a lock carried by the box to lock the box by means of said keepers to the 80 base as and for the purposes described.

2. The combination of the base, the box having a lid, and the single lock in the box for securing the box to the base and for locking the lid, the bolts of said lock for the lid 85 and the base being arranged one in advance of the other, respectively, so as to release the box from the base without opening the lid, substantially as described.

3. The combination of the base having 90 keepers, the box having openings in its bottom to receive the keepers, and provided with the lid having a keeper, and the double sliding bolt in the box having the locking ends arranged to lock the box to the base keepers 95 and the lid on the box, the base keeper locking ends being shorter and arranged to release the box from the base before the lid is released, substantially as described.

4. The combination of the base, the box 100 having the lid, and the double locking bolt arranged to lock the box to the base and the lid on the box, said bolt provided with the tumblers having stops arranged to hold the bolt at an intermediate point in locking position in relation to the lid and unlocked position in relation to the base, substantially as described.

5. The combination of the base, the box having the lid, and the double locking bolt 110 having its locking ends to secure the box to the base shorter than its locking ends to secure the lid, as and for the purposes set forth.

6. The combination of the base, the box having a lid, and the double locking bolt 115 provided with the tumblers having stops arranged to hold the bolt out of locking relation with the base and a spring yieldingly holding said bolt, while in said position, in locking relation with the lid. 120

7. A box having a spring actuated false bottom and a concealed spring actuated catch for holding the said bottom in its normal lowered position.

8. A safe box having the false bottom pivoted at one edge, a sliding bar in the lock containing compartment of the box holding said lid down and having a controlling lever located near an opening in said compartment, and a spring to throw up said bottom 130 when released.

9. A safe box having the lock containing compartment provided with openings in its upper edge to receive the lid keeper, a swing-

ing false bottom in said box, a spring catch therefor in said compartment, and means, as described, for releasing said catch located beneath one of said openings so that it can be operated by an instrument inserted through said opening, substantially as set forth.

10. The combination of a base, a safe box having a lid, and a double arm spring controlled bolt arranged to lock the box to the base and the lid on the box, said bolt at its limit of movement in one direction releasing the box from the base, and the lid from the

box, and having tumblers arranged to hold the bolt at an intermediate point in its movement, locking the lid on the box, but releasing the box from the base as set forth. 15

In testimony that I claim the foregoing as my own I affix my signature in presence of two witnesses.

ERNEST MEYERS.
